CLAIM

The ornamental design for a display screen with graphical user interface, as shown and described.

DESCRIPTION

FIG. 1 is a front view of a display screen with graphical user interface showing our new design; and, FIG. 2 is a front view of the display screen with graphical user interface shown in FIG. 1, with broken line elements omitted for clarity.

The broken line showing of the text, the numerals, the various icons, the various tile portions, the remainder of the user interface and the remainder of the display screen is for environmental purposes only and forms no part of the claimed design.
